UNITED STATES PATENT OFFICE.

ELLIS D. ALLENSTORTH, OF WAUKEGAN, ILLINOIS.

IGNITION APPARATUS.

1,213,789.

Specification of Letters Patent. Patented Jan. 23, 1917.

Application filed August 30, 1915. Serial No. 48,105.

To all whom it may concern:

Be it known that I, ELLIS D. ALLENSTORTH, a citizen of the United States, residing at Waukegan, in the county of Lake 5 and State of Illinois, have invented certain new and useful Improvements in Ignition Apparatus, of which the following is a specification.

One of the objects of my invention is to 10 generally improve devices of this character.

Another and more specific object of my invention is to simplify and cheapen the cost of construction and to render the parts 15 accessible for observation, adjustment and repair.

Other and further objects of my invention will become readily apparent to persons skilled in the art, from a consideration 20 of the following description when taken in conjunction with the drawings, wherein:—

Figure 1 is a central vertical section of the device. Fig. 2 is a plan view thereof. Fig. 3 is a transverse section taken on line 3—3 of Fig. 1. Fig. 4 is a transverse section 25 taken on line 4—4 of Fig. 1.

In all the views the same reference characters are employed to indicate similar parts.

The major portion of the device is the 30 housing, or casing 5, having an axially concentric integral sleeve 6 and a laterally projecting arm 7, the latter having a flat extension or prolonged plate part 8. The sleeve 6 contains another detached, separable sleeve 9 upon which the casing is freely 35 rotatable and which is provided with an annular flange 10 to afford a shoulder 11 upon which the casing rests. The flange 10 is provided with a set screw 12 by which the 40 device as a whole, may be supported on a shaft, such as indicated at 13 by dotted lines. To hold the sleeve 9 within the sleeve 6 I secure, on the top of the former, a block 13 by means of inclined screws 14. Projecting upwardly from the block 13, and 45 concentric with the bore of the sleeve 9, is a stud 15, threaded as at 16 to receive the timer-cam 17 which is also threaded and which engages the threaded portion 16 of the stud 15. The check nut 18 is preferably 50 downwardly curved, and preferably made of spring material such as steel and has threaded engagement with the threaded portion 16 of the stud 15 above the cam and

serves to hold the timer-cam 17 in place 55 upon the stud. A cotter pin 19 passes through the stud 15 and prevents the check nut 18 from backing off of the threaded portion of the stud. The upper end of the stud 15 carries a block of insulating material 20 60 having an axially positioned sleeve 21 adapted to fit the upper end of the stud 15 and another sleeve 22, practically at right angles thereto, screw threaded for a set screw 23, whereby to hold the insulation 65 block 20 firmly in place upon the upper end of the stud. The block 20 is preferably counter-bored, as at 24, in the floor of which counter-bore is located a secondary conductor 25, which projects laterally and upwardly from one side of the block, as at 26, for electrical association with the terminal screws 27—27. A cap or cover 28, preferably of insulating material, is secured to the casing 5, as by screws 29—29 and carries the 75 terminal screws 27—27. It also carries an axially located central terminal screw 30 which forms a terminal for one side of the high potential distributing circuits. The lower end of the terminal 30, to wit, the end 80 31, is counter-bored, as at 32, to receive a carbon plug 33, which is held yieldingly upon the upper surface of the conductor 25 by means of a coiled open spring 34, thereby to complete electric continuity between the 85 terminal 30 and the conductor 26.

A laterally reciprocable hollow shaft 35 is contained in a radial bore in the arm 7 and carries a pin 36 that slides freely in a slot 37 of said bore, thereby to prevent the 90 shaft 35 from rotating but permitting its easy reciprocation. The shaft 35 is enlarged into a head, at its inner end, as at 38, to provide a shoulder 39 for the open helical spring 40, the other end of which 95 bears against a shoulder 41 provided on the casing, thereby to cause the shaft 35 to be held yieldingly in its inwardly extended position. The head 38 of the shaft 35 contains a roller 39, which is freely rotatable 100 upon a pin 40 movable in the slot 41, in said head. The inner end of the bore of the shaft 35 is screw threaded, the outer end of which, however, is smooth and is of somewhat smaller diameter to contain an 105 independently reciprocatable pin 42. This pin is reduced at its outer end, as at 43, and carries a contact point of suitable character.

22

44, the reduced end projecting through a perforation in the end of the shaft 35, which will not permit the larger portion 42, of the pin to pass through on account of the shoulder existing between the parts 42 and 43. 5 A spring 46, yieldingly holds the shoulder, provided by the larger portion 42, against the shoulder in the end of the shaft 35 and is adjustable in effect by the stud screw 47. 10 The spring 40 serves to hold the roller 39 in neat contact with the timer-cam 16 and the spring 46 serves to hold the shoulder, provided by the larger portion 42 of the pin, in yielding contact with the shoulder provided by the hollow shaft 35. 15 A relatively stationary contact 50 is provided on the reduced end 52 of the adjustable fixed screw 53. The contact 50 co-operates with the contact 44 provided on the outer end of the pin 42. The adjustable screw 53 is held in adjusted position by means of a clamping screw threaded part 55 having a threaded shank extension 56 for a wire binding nut 57, provided for completing the primary circuit of the spark producing system. The part 55 is slotted or divided, and is provided with two projecting ears 54 and 55. Through these ears pass a clamping screw 56. There is a clearance hole in the part 55 to permit the clamping action. After the adjusting screw 53 has been moved to selected position the clamping screw is tightened so as to draw the ears 54 and 55 in closer contact thereby to clamp and hold the shank of the adjusting screw in the position in which it has been placed by said adjustment. The part 55 is insulated on the flat portion 8 of the casing, by means of insulating plates or washers 58, 30 59 and 60. Another plate of insulating material 61 is threaded and passes over the inner end of the adjusting screw 53 and is held in place thereon as the result of its flat underportion which contacts with the upper portion of the plate 8. 35 A spark-gap cover 62, consisting of a piece of spring sheet metal such as steel or bronze is hinged, as at 63, to the plate 8 and is provided with a curved latch end 64, which 40 snaps into the groove provided on the plate 8 when the cover is in position. The outer edge of the cover rests on the plate of insulating material 61 and prevents short-circuiting of the primary circuit by contact 45 with the part 55. This cover closes the spark gap space within which the primary circuit is broken by the contacts 44 and 50 but renders the contacts readily accessible for observation or adjustment by simply 55 moving the clip 64 and lifting the part 62 of the cover.

When the parts fixed to the sleeve 9 are rotated the radially positioned shaft 35 is moved outwardly by the timing cam 17 until 60 the contact 44 is in connection with the

relatively stationary contact 50 after which any further outward axial movement of the shaft 35 is taken up by the spring 46, in the relative movement of the shaft 35 and the pin 42. By this means making a firm, positive connection between the two contacts of the primary circuit for relatively a protracted period of time, and producing a hammer break action when the circuit is broken, thereby causing a large and very effective spark to be produced within the combustion chamber of the engine.

To disassemble the parts it is only necessary to remove the cover 28 after which the screws 14—14 may be taken out and the movable parts may all be readily and quickly separated. The roller 39 will readily leave the head 28 of the shaft 35, as a result of the slot 41, after which the pin 35 may be removed from its bore and the shaft 42 may be readily taken from its position by taking out the stud screw 47, and the spring 46. From the construction above described it is evident that the parts are readily accessible for oiling and adjustment or disassembling to substitute new parts.

I have shown only one cable terminal 65, though it is of course evident that each of the terminal screws 27 and 30 is to be supplied with a similar terminal.

The extended end of the plate 8 is bored, as at 66, by means of which connection can be made to the casing for the purpose of oscillating it to change the cyclic spark time relation of the device with the piston of the engine, as usual in devices of this character. It is also manifest that by changing the number of terminals 27 and correspondingly changing the cam 17 the device may thus be adapted for an engine of any desired number of cylinders.

While I have herein shown a single embodiment of my invention for the purpose of clear disclosure, it will be manifest that many changes may be made in the general form, arrangement and configuration of the parts, within the scope of the appended claims.

Having described my invention, what I claim is:

1. A device of the character described comprising a casing having a laterally projecting part provided with a radial bore; a hollow shaft axially movable within said bore; a roller carried by the inner end of said shaft; a timer-cam rotatable on an axis at substantial right angles to said hollow shaft and in a horizontal plane with said roller; a spring to yieldingly hold said roller in contact with said cam; a contact pin, within the hollow shaft, having a contact-bearing end projecting from the end thereof; a spring within the hollow shaft to yieldingly hold the contact pin in its extended position; a stop for said contact pin

and a relatively stationary contact for co-operation with the said movable contact.

2. A device of the character described comprising a casing, having a laterally projecting part provided with a radial bore and a plate extension; a hollow shaft, axially movable within said bore; a removable roller carried in a slot provided in the inner end of said shaft; a timer-cam rotatable on an axis at substantial right angles to said hollow shaft, in a horizontal plane with said roller; a spring surrounding said hollow shaft, to yieldingly hold said roller in contact with said cam; an axially movable contact pin, within the hollow shaft, having a contact-bearing end projecting from the end of said hollow shaft; a spring within the hollow shaft to yieldingly hold the contact pin in its extended position; a stop for said contact pin; a relatively stationary, adjustable contact for co-operation with the movable contact, insulatedly supported on said plate extension and a cover for the spark-gap space between said contacts.

25 3. A device of the character described comprising a casing having a laterally projecting part provided with a radial bore; an axially movable contact member within said bore; a relatively stationary, adjustable contact member without the bore; a rotatable part on which the casing and both contacts are rotatably supported; a distributor cam carried by a part rotatable independently of

said casing, and a commutator member for the high potential circuit carried by said 35 rotatable support.

4. In an ignition timer the combination with a cam reciprocated member having an opening therein, of a contact member extending within the opening, a spring to resiliently hold the contact member in its extended position, a stop to limit the outward movement of the contact member, and a relatively stationary coöperating contact member.

45 5. A device of the character described comprising a casing having a laterally projecting part provided with a radial bore; a hollow shaft axially movable within said bore; a timer cam; a spring to yieldingly hold the inner end of said shaft in contact with said cam; a contact pin, within the hollow shaft having a contact bearing end projecting from the end thereof; a spring within the hollow shaft to yieldingly hold the 55 contact pin in its extended position; a stop for said contact pin; and a relatively stationary contact for co-operation with the said movable contact.

In testimony whereof I hereunto set my 60 hand in the presence of two subscribing witnesses.
